UNITED STATES PATENT OFFICE

RAYMOND BOOTH, OF CITY ISLAND, NEW YORK

COLLAPSIBLE TUBE AND COVER

Application filed October 29, 1931. Serial No. 571,763.

This invention has reference to closures for containers especially to the kind that are known as collapsible tubes, used for holding various substances in the nature of a paste, that can be readily extruded through the reduced opening at the top by pressure on the side walls; and which tubes are provided with a suitable closure, that is usually a threaded cap, that must be removed for delivery of the contents, and which frequently becomes lost.

The object of the present invention is to provide a device of this character with a special form of closure, that is hinged to the delivery end, and retained closed by a suitable locking means, and which closure or cap is provided with means, at once swinging it to the open position, on release of the locking means.

In the accompanying drawings showing one embodiment of my invention:

Figure 1 is a top plan view.

Fig. 2 is a transverse section at the delivery end.

Fig. 3 is a partial prospective view at this end.

Fig. 4 shows the cap detached.

Fig. 5 is an axial section at the upper end.

Fig. 6 shows the spring separately.

Fig. 7 is a reduced view of the entire device.

Fig. 8 shows another form of spring.

As shown in the drawings, the tube 2 has a reduced tubular extension 3, connected with the body by a conical wall 4. The extension is shown as having the outer wall 5 conical and preferably curved.

The cap is shown in the form of an end wall 6, and a side conical wall 7. Lugs are provided on the cap, and on the extension, that are apertured to receive a hinge pin, so that the cap can swing from a position closing the extension, to a fully open position as indicated in Fig. 5. As shown, I provide lugs 8 and 9 on the tube extension, with suitable apertures, and the cap side wall 7 is provided with an apertured lug 10. A pin 11 passes through these apertured lugs as shown, and will support the cap to swing in the manner set forth.

Suitable locking means are provided to hold the cap in the closed position, such as a lug or projection on one of these members, and a similar socket or cavity in the other member, so that the natural spring or elasticity of the cap, usually made of thin sheet metal, will cause the lug to enter the cavity, as shown. The extension is provided with a lug 12, and the cap with a portion depressed from the inner wall to form a socket 13, that when the cap is swung to closed position will cause the cap to spring out, and then the socket portion will engage the lug and hold the cap in closed position. Preferably an extension 14 is provided on the cap, in the nature of an ear or finger piece, whereby the user can press this part of the cap outwardly, and upwardly, to open the tube.

Means are further provided for swinging the cap to the open position as soon as the locking means for the cap has been released, which is preferably in the form of a small flat spring strip 15, shown in Fig. 6. This spring has a curved portion 16, and a rather flat portion 17 at one end with the extremity 18 bent downwardly. The extension is provided with a flat wall 19 below the hinge that contains a small slot 20 adapted to receive the bent end 18 of the spring. Before the cap is applied by the hinge arrangement, this slot, that is exposed between the lugs 8 and 9, will have the end 18 of the spring inserted, and the adjacent wall 15 will rest on the flat wall 19, with the curve portion 16 extending upwardly. Then the cap is applied by the hinge pin, and the lug portion 10 of the cap will be positioned directly above the spring at its mounting, and will lock the spring in this position. The curved end of the spring will engage the inner wall of the cap, and this curve is so designed that when the cap is swung to the closed position, its engagement with the end of the spring will pull it over bending it into a socket portion 21 in the extension, as indicated in Fig. 5. The locking means will hold the cap in the closed position. When access is desired to remove the contents of the tube, the finger piece 14 is pressed outwardly to release the cap at the lock, and this tensioned spring 15 will at once

swing the cap to the fully open position, as indicated in Fig. 5. Instead of the plate spring shown in Fig. 6, I have used a spring 22, made from a piece of spring wire, with the bent 23 at one end in which case the opening 20, in the extension is merely a round hole instead of a flat slot. See Fig. 8.

It will be seen that a device of this character is very simple and of low cost of production, the tube is simply molded to the form shown, by suitable dies, and the lugs will have the holes made therein.

The cap is pressed out of sheet metal in the usual manner, that is a simple operation.

10 The plate spring is simply bent to the form shown; and the tube is provided with the hole 20 for the spring. To assemble these parts the spring is simply placed in position, the cap applied and the hinged pin inserted and 20 secured, when the device is ready for use.

What I claim is:

1. In a closure for a collapsible tube, a tube having at the reduced end a tubular extension of conical form on its outer wall and 25 provided at the base of the extension with a pair of spaced apertured lugs, a cap having a top with the sides of conical form slightly larger in the inner walls to engage said extension outer wall, the cap having an apertured lug at the base adapted to fit between said lugs, a hinge pin located in the lugs of the cap and of the extension whereby the cap can swing from a closed position in engagement with the said extension wall back 30 to a fully open position, the cap and extension having means to lock the cap in the closed position, the tube at the base of the extension directly below said hinge pin being provided with a flat wall containing a 35 hole extending downwardly, and a spring having one end portion bent at a right angle to be inserted in said extension hole with the spring engaging the said flat wall, which spring is located beneath the hinge lug of the cap and thereby retained in such position, the spring beyond said end portion extending upward with its extremity engaging the inner wall of the cap and under tension when the cap is closed to swing the cap to 40 the open position on release of the cap at its said locking portion.

2. In a closure for a collapsible tube, a tube having at the reduced end a tubular extension of conical form on its outer wall and 55 provided at the base of the extension with a pair of spaced apertured lugs, a cap having a top with the sides of conical form to engage said extension outer wall, the cap having an apertured lug at the base adapted to fit between said lugs, a hinge pin located in the lugs of the cap and of the extension whereby the cap can swing from a closed position in engagement with the said extension wall, back to a fully open position, the cap and extension 60 having means to lock the cap in the closed position.

the hinge having a lug on one member and a socket on the other member adjacent the cap margin to lock the cap in the closed position, the tube at the base of the extension directly below said hinge pin being provided with a flat wall containing a slot extending downwardly, and a spring having one end portion bent at a right angle to be inserted in said extension hole with the spring engaging the said flat wall, which spring is located beneath the hinge lug of the cap and thereby retained in such position, the spring beyond said end portion extending upward with its extremity engaging the inner wall of the cap and under tension when the cap is closed to swing the cap to the open position on release of the cap at its said locking portion.

3. In a closure for a collapsible tube, a tube having at the reduced end a tubular extension of conical form on its outer wall and provided at the base of the extension with a pair of spaced apertured lugs, a cap having a top with the sides of conical form to engage said extension outer wall, the cap having an apertured lug at the base adapted to fit between said lugs, a hinge pin located in the lugs of the cap and of the extension whereby the cap can swing from a closed position in engagement with the said extension wall back to a 70 fully open position, the cap and extension on the side opposite the hinge having a lug on one member and a socket on the other member adjacent the cap margin to lock the cap in the closed position, the cap having an ear projecting outward at the locking portion to release the cap when locked, the tube at the base of the extension directly below said hinge pin being provided with a flat wall containing a slot extending downwardly, and a spring having one end portion bent at a right angle to be inserted in said extension hole with the spring engaging the said flat wall, which spring is located beneath the hinge lug of the cap and thereby retained in such position, the spring beyond said end portion extending upward with its extremity engaging the inner wall of the cap and under tension when the cap is closed to swing the cap to the open position on release of the cap at 80 its said locking portion.

4. In a closure for a collapsible tube, a tube having at the reduced end a tubular extension of conical form on its outer wall and provided at the base of the extension with an apertured lug, a cap having a top with the sides of conical form slightly larger in the inner walls to engage said extension outer wall, the cap having an apertured lug at the base, a hinge pin located in the lugs of the cap and of the extension whereby the cap can swing from a closed position in engagement with the said extension wall, back to a fully open position, the cap and extension having means to lock the cap in the closed 90 position.

position, the tube at the base of the extension directly below said hinge pin being provided with a flat wall containing a slot extending downwardly, and a spring having one end portion bent at a right angle to be inserted in said extension hole with the spring engaging the said flat wall, which spring is located beneath the hinged lug of the cap and thereby retained in such position, the spring beyond said end portion extending upward with its extremity engaging the inner wall of the cap and under tension when the cap is closed to swing the cap to the open position on release of the cap at its said locking portion.

Signed at New York, N. Y. on this 26th day of October 1931.

RAYMOND BOOTH.
